UNITED STATES PATENT OFFICE

ABRAHAM REBEL, OF BROOKLYN, NEW YORK, ASSIGNOR TO THE DE LONG HOOK AND EYE COMPANY, OF PHILADELPHIA, PENNSYLVANIA, A CORPORATION OF PENNSYLVANIA

NEEDLE-PROTECTING ATTACHMENT FOR SEWING MACHINES

Application filed November 15, 1926. Serial No. 148,413.

In sewing hook and eye tape upon garments to provide the latter with fastening means whereby adjoining edges thereof may be secured together difficulty heretofore has been 5 encountered by reason of the fact that the needle of the sewing machine is liable to strike a wire, either of a hook or of an eye, which may result either in the breaking of the needle or in the cutting of the wire there- 10 of rendering the hook or the eye, as the case may be, useless.

The principal difficulty encountered has been in connection with the sewing of the tapes which bear the loop eyes upon the edges 15 of garments, and the principal object, therefore, of the present invention is to provide means of novel construction whereby the spaced wires of the eye member of a hook and eye structure may be automatically ad- 20 justed or moved to positions during the sewing operation out of alinement with the de- 25 scending point of the reciprocating needle of the sewing machine.

It also is an object of the invention to 25 provide an attachment of novel construction which, when sewing a fabric having wires located at intervals thereon, is adapted to 30 control the positions of the said wires with respect to the descending point of the recipro- 35 cating needle of a sewing machine so as to prevent the point of the said needle from 40 striking said wires.

Another object of the invention is to pro- 35 vide an attachment having a guard finger 40 which, as the needle descends to penetrate the fabric, moves into a position relative to the penetrating point of the needle to guard the latter and to prevent the same from con- 45 tacting with a wire which may be mounted 50 on the fabric along which a line of stitches is being formed.

Although I have illustrated the invention as employed in connection with the sewing of a tape having loop eyes of a hook and 45 eye structure mounted thereon I desire it to be understood that the invention is adapted for employment in connection with the formation of stitches in any fabric which 50 stitches cross wires fastened thereon at intervals; and although the opposite sides of

the respective eyes illustrated in the drawings are in substantial parallel relation to each other I desire it to be understood that the invention is not limited in its scope to or for use in the sewing upon the eye tape 55 of a hook and eye structure having eyes of the construction shown, or in the sewing of such tape to a fabric.

I shall not at this time undertake to point out all of the various objects and advantages 60 incident to my invention, but other objects and advantages thereof will be pointed out in the detailed description thereof which follows or will be apparent from such description. 65

In order that the invention may be readily understood and its practical advantages fully appreciated reference may be had to the accompanying drawing in which I have illustrated one form of a convenient embodiment 70 thereof. However, it will be understood that the invention is susceptible of embodiment in other forms of construction than that shown and that various changes in the details of construction may be made within the scope 75 of the claims without departing from the said invention or the principle thereof.

In the drawing,--Fig. 1 is a view in trans- 80 verse section of a portion of a sewing ma- 85 chine provided with an attachment embody- ing the invention, the said attachment being shown partly in section and partly in side elevation;

Fig. 2 is a plan view of the top plate of 85 a sewing machine showing the feed dog in plan, a portion of the attachment also in plan, and a section of eye tape and fabric secured together by rows of stitches produced by the sewing mechanism;

Fig. 3 is a view showing a portion of the 90 top plate of the sewing machine in section and showing one end portion of the guard finger in its highest position and with the needle moving upwardly;

Fig. 4 is a view showing the rear end por- 95 tion of the guard finger in elevation and in the act of starting upon its downward and rear- 100 ward movement, with the needle still moving upwardly but just about ready to start upon its descending movement, and also showing

the wires of an eye in cross section and showing in section the tape upon which the said eye is mounted;

Fig. 5 is a view showing the needle in the act of descending and in approximately the position it occupied at the moment that the guard finger has reached its lowest and most rearward position;

Fig. 6 is a view showing the guard finger in the same position as it is shown in Fig. 5, but showing the needle in the act of penetrating the work, and also showing the relation of the guard finger to the needle and to one side of the eye of a hook and eye structure;

Fig. 7 is a view in plan elevation showing a needle in section, the guard finger being shown in full lines in the position it occupies in Fig. 3 and also in dotted line position in engagement with one side or leg of an eye, the latter in its adjusted position also being shown in dotted lines;

Fig. 8 is a view showing the rear portion of the guard finger in elevation and the wire in cross section and also showing one relationship which may exist between the extreme rear end of the guard finger and the wire when the former is approaching the limit of its rearward and downward movement;

Fig. 9 is a similar view but showing a different relationship between the guard finger and the wire with the guard finger in the same position as it is shown in Fig. 8;

Fig. 10 is a view showing the rear end portion of the guard finger in side elevation with its rear lower end in contact with a wire at a point beyond a vertical plane through the axis thereof and also showing a portion of the needle in elevation and also showing the tape in section; and

Fig. 11 is a view similar to that shown in Fig. 10 except that the guard finger has moved into final position displacing the wire toward the front of the machine out of alignment with the axis of the needle which has descended so that it is about to enter the work.

The views showing the several figures of the drawings 3 to 11 inclusive are intended to illustrate the operation of the device and its cooperation with the needle and with wires which may be carried upon a tape or other fabric for adjusting the said wires out of alignment with the point of the needle as the latter descends to enter the work.

For the purpose of illustrating the operation of the invention I have shown a section of tape 1 having loop eyes 1^a mounted thereon at intervals. The opposite sides of these eyes are arranged in parallel relation to each other as shown.

In the drawings I have shown but a portion of a sewing machine including a top plate 2, the main driving shaft 3, a presser foot 4, a presser foot supporting bar 5 and a four-motion feed dog 6. I also have shown the sewing machine needles 10 mounted upon

a reciprocating bar 11, reciprocation of which may be effected in any known manner. The several parts of the machine referred to are of well known construction and operation and will not, therefore, be described more in detail.

For the purpose of guiding the tape 1 to the needles I have provided the adjustable spaced guides 12 and 13 which are mounted upon the top plate of the machine. These guides are of usual construction and their operation and function are well understood in the art. In the attachment of a tape to the edge of a fabric the latter is conducted to the sewing mechanism through a folder which is of any known construction and for that reason is not illustrated or shown in the drawing.

The tape 1 bearing the eyes 1^a is attached to the fabric by double lines or rows of stitches as shown at 14. One of these lines or rows of stitches crosses the loop eyes at points intermediate the ends of the opposite sides thereof as is shown in the drawings. This line or row of stitches occupies the same relationship to the ends of the opposite sides of the loop eyes as has heretofore been customary. It is to be understood, however, that I prefer to employ in connection with the device embodying the invention loop eyes in which the opposite sides are arranged in substantially parallel relation to each other, but this relationship is not essential to the invention.

Mounted upon the forward edge of the top plate 2 of the machine I have provided a bracket 15 having bearings within which a rock shaft 17 is mounted. An arm 18 rigidly secured in any desired adjusted position to the said shaft depends therefrom and is connected at its lower end to a link 19 the rear end of which is connected to an eccentric 20 which is integrally or otherwise connected with a block 21 which is adjustable upon the sleeve 22 mounted upon and to rotate with the main shaft 3 of the machine. Adjustment of the block 21 may be effected by adjusting the screw 23 in known manner, and after having been adjusted may be held in adjusted position by the binding screw 24. It will be noted that the eccentric 20 is hollow or tubular and that its internal diameter is greater than the external diameter of the shaft 3 whereby adjustments of the said eccentric may be effected. No further details of description of the eccentric will be given because it is of known construction. The position of the eccentric controls the extent of movement of the arm 18 and consequently the extent of the rocking or oscillatory movements of the shaft 17 previously referred to.

An arm 25 is adjustably connected to the shaft 17 and projects upwardly and toward the front of the machine. To its upper end an extension 26 is adjustably connected by

means of a connecting or binding screw 27. To the upper end of the extension 26 is connected, integrally or otherwise, a rearwardly extending arm 28 which projects part-way over the table 2. It will be noted upon reference to Fig. 2 that the arm 28 is located out of alignment with the presser foot, its location being to the left thereof to a person sitting in front of and facing the machine. A finger 30 is adjustably mounted upon the arm 28, being secured thereto by means of a binding screw 31 which extends through a slot 32 in the finger 30 and engages a tapped opening in the arm 28. By loosening the screw so as to release the head thereof from contact with the finger 30 the latter may be moved either toward the front of the machine or the rear, as may be desired. The adjustments in the extent of the rocking movements of the shaft 17, of the arm 25, the extension 26, and the finger 30 are provided in order that the rear end of the finger 30 may be caused to operate in proper relation to the adjoining needle 10.

The rear end portion of the finger 30 extends laterally toward the sewing mechanism, as indicated at 35, and then downwardly as indicated at 36 and terminates in a pointed portion 37. The front edge of the downwardly extending portion 36 is tapered downwardly and rearwardly, as is clearly shown in Figs. 3 to 6 and 8 to 10 of the drawings. The parts in said figures are shown on an enlarged scale for the sake of clearness. At and adjoining the rear lower end of the finger 30 the front edge thereof is curved rather sharply rearwardly, as indicated at 38. The purpose of the formation of this edge will be referred to more in detail later on herein. The rear edge of the rear lower end of the finger 30 is notched, as indicated at 40, for the purpose of engaging a wire, should occasion for engagement thereof arise, to move the same rearwardly out of the path of the descending point of a needle during a stitch forming operation.

The mechanical features of the device having been described, I shall proceed with a description of its operation as follows:

In this description I shall start with Fig. 3 of the drawings, in which the finger 30 has just arrived at its highest and most forward position. At such time the needle in its ascending movement will have reached a position substantially as is shown in full lines in said figure. From this position the finger 30 begins its return or rearward movement after having been stationary for a very short fraction of time, the actuating eccentric 20 at the moment of the beginning of the return or rearward movement occupying a position 180° different from that in which it is shown in Fig. 1. The needle continues its ascending movement until it finally arrives at the position indicated in dash-and-dot lines in Fig. 3 and in full lines in Fig. 4. It then begins its

descending movement but it does not reach the work until the point of the projection 37 upon the finger 30 has arrived at its lowest and most rearward point or position, slightly in rear of the point in the fabric at which the penetration thereof by the needle takes place, as illustrated in Fig. 1. While the projection 37 is in its rearmost position and while the needle 10 is penetrating the material the actuating eccentric 20 is in substantially the position shown in Fig. 1 of the drawing. It will be understood that the finger which is actuated by the eccentric 20 will make a slight pause at each reversal of its direction of movement and also that at such time the said eccentric occupies either the position shown in Fig. 1 or a position differing by 180° from that position. The eccentric being in one or the other of these positions when reversal of the direction of movement of the finger 30 takes place, it follows that for short periods of time the said finger moves relatively slowly as compared with other parts of its movements.

Just about as the projection 37 on the finger 30 reaches its rearmost and lowest position the four-motion feed arrives at its rearmost position and the said feed then descends and both the feed and the finger carrying the projection 37 begin their movement toward the front of the machine, and continue such movement until the needle (which has penetrated and passed through the work and is ascending) again arrives at approximately the position shown in full lines in Fig. 3 on its next ascending movement. It will be apparent that the eccentric 20 through the connections as shown in Fig. 1 actuates the finger 30 in such relation to the movements of the needle 10 that just prior to the time when the needle reaches penetrating relation with respect to the fabric of the work being operated upon the said projection will reach the position shown in Fig. 1 and will contact with any wire which may happen to be in the path of the needle to adjust the same out of such path and thereby prevent the striking of such wire by the needle in its descending movement.

It will be understood that the needle referred to in the foregoing description of the operation is that which is located nearest to the extreme rear end of the finger 30, as shown in Fig. 2 of the drawings.

As is shown in Fig. 6 of the drawings, the point of the needle 10 is a short distance out of alignment with the extreme lower end 37 of the finger 30 when the latter is in its rearward and lowermost position. It however will be apparent that the pointed end portion 37 of the finger may be so shaped as to permit location of the extreme point of said finger in alignment with the needle when looked at from the side. The construction as shown is that which is preferred by me at the present time.

Upon reference to Figs. 6 and 7 of the draw-

ings it will be apparent that when a wire constituting one side of an eye, such as is shown in the drawings, is in position within the notch 40 said wire may occupy a slightly 5 angular position, as indicated in dotted lines in Fig. 7, with respect to the length of the tape upon which the eye is mounted, and that the portion thereof adjacent the line of movement of the needle is sufficiently displaced 10 rearwardly to prevent the point of the needle from contacting therewith. Consequently the wire is not in position to interfere with the passage of the needle through the fabric.

If the wire constituting one side of an eye 15 should occupy a position in contact with the front edge of the pointed portion 37 of the finger 30, as shown in Fig. 11, the said wire will be held in position in front of the line of movement of the point of the needle so that 20 the latter will be permitted to enter the fabric without injury to the needle. It may be that one side or the other of the needle in the two positions described may contact with the wire, but such contact does not injure the needle or 25 interfere with its penetration of the work.

As already indicated, the finger 30 starts upon its ascending movement or movement toward the front of the machine at a time after the needle has penetrated a considerable 30 distance through the work but while it is still descending and continues said movement until the needle has returned to approximately the position shown in full lines in Fig. 3. If, however, an eye should have been dis- 35 placed into abnormal position it would have been by this time returned or partially re- turned to normal position by the contact of the curved forward edge of the end portion 38 of the finger 30. It is after this time that the 40 tensioning means of the sewing machine op- erates to tighten the stitch. It will be seen, therefore, that the stitch will be tightened upon the wire of the eye after the latter is 45 returned to substantially normal position even though at a previous time it may have occupied an abnormal position.

In the operation of the protective or guard finger 30 it may happen that the extreme 50 point of the end portion 37 will contact with the wire at some time in front of a vertical plane through the axis thereof, as is indicated in Fig. 8. In such case the wire will be ad- justed rearwardly into the position indicated by the dotted lines in Fig. 7. If, however, 55 the point of the end portion 37 should con- tact with the wire at a point in rear or to the left of a plane through the axis of the wire, as shown in Fig. 9 of the drawings, the front edge of the portion 37 will operate to cam the 60 wire toward the right into the position shown in Fig. 11 with relation to the lower end por- tion 36, 37 of the finger 30.

It will be noted that the path of movement 65 of the point of the projection 37 from and to the position in which it is shown in Fig. 1 is

due to the relation of that position to the axis of the shaft 17 and to a vertical plane includ- 70 ing the said axis and at right angles to the plane in which the said view is taken. The point of the projection 37 when in the posi- tion shown in Fig. 1 is in a radial line from the axis of the shaft 17 which forms an acute angle with the vertical plane referred to. It is apparent, therefore, that upon oscillation of the arm 25 the point of the projection 37 reciprocates through the arc of a circle of 75 which the axis of the said shaft is the center, which arc extends in angular relation to the top surface of the table by which the fabric of the work is supported and to the plane of 80 the fabric supported on said table.

It will be seen that by my invention I have provided means by the employment of which the point of the needle in its descending move- 85 ments is efficiently and effectively prevented from contacting with a wire which normally occupies a position at right angles to a tape or to a fabric, or at right angles to the line of movement of such tape or fabric through the machine. As a result of the employment 90 of a device embodying the invention the breakage of needles due to the contact thereof with wires which may be secured to the work being operated upon, or the cutting of such wires by the contact of the needle therewith is 95 absolutely prevented. This results not only in a great saving in operation but in great economy as well.

Having thus described my invention, what I claim and desire to secure by Letters Pat- 100 ent is:

1. A needle protecting attachment for sew- 105 ing machines comprising a reciprocating finger the outer free end of which is provided with a downwardly extending projection which contacts with a wire which is secured to the work and extends transversely of the path of movement of the work as it moves through the sewing machine and which may happen to be located in the path of down- 110 ward movement of the needle, and means for effecting reciprocation of the said finger which means causes movements of the said finger in such correlation to the movements of the needle that said downwardly extend- 115 ing portion of said finger reaches a point in proximity to the point of penetration of the work by the needle in advance of the said needle and contacts with any wire which may be in alignment with the point of the descending needle and displaces the same with respect to the point of the needle.

2. A needle protecting attachment for sew- 120 ing machines comprising a rocking shaft, means for effecting rocking movements there- 125 of, an arm extending from said shaft to a point above the plane of the top plate of the said sewing machine, and a finger secured to the said arm and extending over the top plate of the said machine and terminating in op- 130

- erative relation to a needle of the sewing machine, the movements of the said finger being so related to the movements of the said needle that the end of said finger arrives at a point in proximity to the work and in proximity to a point of penetration of the work by the needle in advance of the said needle, the end of the said finger contacting with and displacing a wire which may be located in the path of the needle.
3. An attachment for sewing machines for protecting the needle and a wire which is mounted upon a fabric which is being fed through the machine comprising a protecting member, means for adjustably supporting the said protecting member with the operative portion thereof in operative relation to a needle of a sewing machine, and means for effecting reciprocating movements of said member which means moves the operative end of said member into proximity to the work and to the point of penetration of the work by the needle in advance of the penetration of the work by the needle and to retain the same in such position until after the needle has penetrated the work, the said operative end contacting with and displacing any wire which may be located in the path of the needle.
4. An attachment for sewing machines for protecting the needle and a wire which is mounted upon a fabric which is being fed through the machine comprising a finger supported at the front of a sewing machine and extending rearwardly over the top plate thereof toward the rear of the machine, the rear end of the said finger terminating in the region of the stitch-forming mechanism of the sewing machine, and means for effecting reciprocation of the said finger toward and from the sewing mechanism which means causes the rear end of said finger to move into position to contact with a wire which may occupy a position in alinement with the needle in advance of the arrival of the needle at the point of penetration of the work and to adjust said wire from such position to a position out of alinement with said needle.
5. A needle protecting attachment for sewing machines comprising a finger the rear end of which terminates in a relatively thin portion which occupies a vertical plane in proximity to and laterally of a needle, the said plane extending in a direction substantially parallel with the direction of the path of movement of the work through the machine, the said attachment operating to adapt said machine for forming rows of stitching in fabrics crosswise of wires mounted at intervals upon said fabric, the said finger contacting with any of said wires which may occupy positions in alinement with the said needle and adjusting them either forwardly or rearwardly into positions out of alinement with the axis of the said needle, and means for effecting movements of the said finger to position the point thereof adjacent the fabric and adjacent the point of penetration of the fabric by the needle in advance of the needle.
6. An attachment for sewing machines for protecting the needle and a wire which is mounted upon a fabric which is being fed through the machine and in which a line of stitching is being formed which extends crosswise of the said wire, comprising a finger the rear end of which terminates in a downwardly extending portion which contacts with a wire which may happen to be located in alinement with the needle in its descending movement and which extends transversely of the said finger and of the path of movement of the work through the machine to effect adjustment of the said wire either toward the front or the rear out of alinement with the axis of a needle; and means for moving the said finger back and forth to cause the said downwardly extending portion thereof to contact with said wire and effect the said adjustment thereof.
7. A needle protecting attachment for sewing machines, comprising a protecting finger which extends from the front toward the rear of the machine, the said finger being located above the top plate of the sewing machine, and means for effecting reciprocation of the said finger, and the said finger being provided at its rear end with a downwardly extending portion the rear lower edge of which is provided with a notch which is adapted to engage a wire which may be mounted upon the work and which extends transversely of the said finger and of the line of movement of the work through the machine to move the same rearwardly out of alinement with the point of the needle, and the front lower edge of the said downwardly extending portion being inclined and curved rearwardly whereby it is adapted upon contact with a wire to effect adjustment of the same toward the front of the machine out of alinement with the point of the needle.
8. In a needle protecting attachment for sewing machines, the combination of a drive shaft, a rocking shaft, an upwardly projecting arm adjustably mounted upon said rocking shaft, an arm mounted upon and projecting laterally from the said shaft, an adjustable eccentric mounted upon the said driving shaft, a link connecting the said eccentric with the last mentioned arm, a protecting finger connected with the upper end of the first named arm and extending over the top plate of the machine and terminating at its rear end in cooperative relation to a needle of the machine, and the rear end of the said finger being provided with means which is adapted to engage wires which may be mounted at intervals upon the work in advance of the needle as it descends to penetrate the work.

- trate the work to effect adjustments of the said wires out of alinement with the descending point of the needle.
9. A needle protecting attachment for sewing machines, comprising, in combination, a protecting member, and means for effecting reciprocating movements thereof in a plane parallel with the direction of travel of the work through the machine, the outer free end of said member arriving at a point in proximity to and laterally of a needle and in a plane parallel with the direction of travel of the work and in proximity to or in contact with the work in advance of the penetration of the work by the needle, the said outer free end contacting with a wire which may be mounted upon the work and which may be in alinement with the needle and causing movement thereof to a position out of alinement with the axis of the needle.
10. A needle protecting attachment for sewing machines, comprising a finger for contacting with a wire which may be mounted on the fabric being stitched and which may be located in the path of movement of said needle, and means for actuating said finger to cause it to contact with the said wire when in such position to displace the same with respect to the said fabric and carry the axis thereof out of alinement with the said needle.
11. A needle protecting attachment for sewing machines, comprising a finger terminating in a downwardly extending pointed portion the front and rear edges of which are shaped to engage a wire which may be carried upon the material being stitched by the said machine and move it into position out of alinement with the needle.
12. A needle protecting attachment for sewing machines, comprising a finger terminating in a downwardly extending pointed portion the front and rear edges of which are shaped to engage successive wires which may be carried at intervals upon the material being stitched by the said machine and which may happen to be located in the path of downward movement of the needle and adjust them relatively to the needle, and means for actuating the said finger to cause it to so engage said wires.
13. A needle protecting attachment for sewing machines, comprising a finger, means for supporting the said finger in a plane parallel with the direction of travel of the work through the machine, and means for reciprocating the said finger to move the free end thereof into and out of position in proximity to the said needle, the rear end of said finger projecting beyond the said needle when it occupies its rearmost position, and contacting with a wire which may be secured to the fabric being stitched by the machine and which may be located in alinement with the
- needle to move it in one direction or another out of alinement with the said needle.
14. A needle protecting attachment for sewing machines, comprising a finger having a pointed end adapted to occupy a position in proximity to the work, a rock shaft, an arm mounted on said rock shaft to which arm said finger is secured, a second arm mounted on said rock shaft, a driving shaft, and means directly connected to the driving shaft and to the second named arm and acting therethrough to oscillate said rock shaft to cause reciprocatory movements of said finger to carry the said pointed end to and from a position laterally of and in proximity to the point of penetration of the needle into the work and in a vertical plane including the axis of the said needle and extending in a direction substantially at right angles with the direction of travel of the work.
15. An attachment for sewing machines for protecting the needle and wires which are mounted at intervals upon a fabric which is being fed through the machine and in which a line of stitches is being formed which crosses the said wires comprising a member having a downwardly extending pointed portion, and means for causing reciprocation of said member to cause the said pointed portion to be moved back and forth to and from a position in proximity to the point at which the said needle penetrates the said fabric, the said pointed portion contacting with and displacing a wire which may happen to be located in the path of the said needle.
16. An attachment for sewing machines for protecting a sewing needle and a wire mounted upon a fabric which is being fed through the machine and in which is being formed a line of stitches which crosses the said wire comprising a reciprocating member having a downwardly extending pointed portion, means for effecting reciprocation of the said member to cause movement of the said pointed portion back and forth past the path of movement of the said needle to a point in adjoining relation to the point at which the needle penetrates the said fabric, the said pointed portion contacting with the said wire if it be located in the path of movement of the said needle to displace the same laterally out of the said path, and means for adjusting the said reciprocating member with respect to the means for effecting reciprocation thereof.
17. An attachment for sewing machines for protecting a needle and a wire which may be mounted upon a fabric which is being fed through the machine and in which a line of stitches is being formed, the said wire extending transversely of the said line of stitches, comprising a downwardly extending wire engaging shoulder, a support for said shoulder, and means for reciprocating the said shoulder back and forth in the direction of

feed to and from a position in proximity to and laterally of the point at which the needle penetrates the fabric, the said shoulder contacting with a wire which may occupy a position in the path of movement of the point of said needle and displacing the same from the said path.

18. An attachment for sewing machines for protecting the needle and a wire which may be mounted upon a sheet of material which is being fed through the machine and in which a line of stitches is being formed, the said wire extending crosswise of the said line of stitches, comprising an arm extending over the top of the table of the sewing machine, which arm is provided at its free end with a downwardly extending projection, and means for actuating the said arm so as to cause the said projection to traverse the arc of a circle which extends in angular relation to the plane of the sheet material which is being fed through the said machine, and means for causing the said projection to arrive at its lowest point in proximity to the point at which the needle penetrates the work at a moment slightly in advance of the moment of penetration of the work by the said needle whereby the said projection contacts with a wire which may happen to occupy a position in the path of movement of the said needle and displaces the same from said path.

19. An attachment for sewing machines for protecting the needle and a wire which may be mounted upon a sheet of material which is being fed through the machine and in which a line of stitches is being formed, the said wire extending crosswise of the said line of stitches, comprising a contact device, means for supporting said contact device laterally of said sheet of material, and means for reciprocating said supporting means and the contact device supported thereby to move the latter to and from a position in proximity to the point at which the needle enters the said sheet of material to cause the same to contact with any wire which may occupy a position in the path of movement of the point of said needle to move the said wire with respect to said path and independently of said material, the path of movement of said device being in a line forming an acute angle with the said sheet of material.

20. A needle protecting attachment for sewing machines comprising a finger terminating at its rear end in a downwardly extending pointed portion, and means for causing reciprocation of the said finger to carry the said downwardly extending pointed portion into and from a position in proximity to and laterally of the point of penetration by the said needle of the material being stitched thereby causing the said downwardly extending pointed portion to contact with a wire which may be carried upon the material being stitched and which may occupy a posi-

tion in alignment with the needle to effect adjustment thereof toward the front or toward the rear into a position out of alignment with the said needle, the rear edge of the said downwardly extending portion being shaped to push the said wire out of alignment with the said needle and the front edge thereof being shaped to cam the same toward the front of the said machine out of alignment with the said needle.

21. In combination with a sewing machine, which machine includes means operating continuously to feed material to be stitched through said machine, a safety attachment for protecting the needle of said machine, the said attachment comprising a finger, and means for moving said finger into contact with a wire member secured to the fabric being stitched and which may happen to come into alignment with the said needle, to move the said member out of alignment with the said needle.

22. In combination with a sewing machine, which machine includes means operating continuously to feed material to be stitched through said machine, a safety attachment for protecting the needle of said machine, the said attachment comprising a finger, means for supporting said finger, and means for operating said supporting means to move the said finger into contiguous relation to the needle whereby the said finger contacts with a wire member secured to the material being stitched and which may happen to be in alignment with the needle to move the said wire member out of alignment with the said needle.

23. In combination with a sewing machine, means for guiding fastener tape to the stitching mechanism of the machine, means operating continuously for advancing the tape toward the said stitching mechanism, and means operating independently of the advancing of the said tape for moving out of the path of the descending movement of the needle of the said stitching mechanism such fasteners on the tape as may happen to come into such path.

24. In combination with a sewing machine, means for guiding fastener tape to the stitching mechanism of the machine, means for advancing the tape toward the said stitching mechanism, and means acting independently of said second named means for moving and holding out of alignment with the needle of said stitching mechanism such fasteners as come into alignment therewith.

25. In combination with a sewing machine, means for guiding fastener tape to the sewing mechanism of the machine, means for advancing said tape and material to which the said tape is to be stitched toward the stitching mechanism of the machine, a safety device for protecting the needle of said mechanism, which safety device comprises a finger, and means for moving said finger into contact

with such fasteners as come into alinement with said needle to move said fasteners out of alinement with the said needle.

26. In combination with a sewing machine, means for guiding fastener tape to said machine, means for advancing said tape toward the stitching mechanism of the machine, an attachment for protecting the needle of said mechanism, the said attachment comprising a finger the end of which is shaped to engage a fastener, means for supporting said finger, and means for operating said supporting means in timed relation with respect to the operation of said needle for causing said finger to contact with such fasteners as come into alinement with said needle and move the said fasteners out of alinement with the said needle.

27. In combination with a sewing machine, means for guiding fastener tape to said machine, means for advancing said tape toward the stitching mechanism of the said machine, a finger for engaging such fasteners as come into alinement with the needle of said mechanism to move said fasteners out of alinement with said needle, and means interposed between the said finger and the drive shaft of the said machine for moving the said finger into and out of engagement with the said fasteners.

28. In combination with a sewing machine, means for guiding fastener tape to said machine, means for advancing said tape toward the stitching mechanism of the said machine whereby fasteners mounted on said tape may be brought into alinement with the needle of said stitching mechanism, means for moving such fasteners out of alinement with the said needle, and means for moving said last named means into a position adjoining the path of said needle in advance of the penetration of the fastener tape by the said needle.

29. In combination with a sewing machine, means for guiding fastener tape to the stitching mechanism of the said machine, means operating without interruption for advancing the said tape toward the said stitching mechanism, means for moving such fasteners as come into alinement with the needle of the said stitching mechanism out of alinement with the said needle, supporting means for the said last named means, and means for oscillating said supporting means.

30. In combination with a sewing machine, means for guiding fastener tape to the stitching mechanism of the said machine, means operating continuously for advancing the said fastener tape toward the said stitching mechanism, means located above the plane of the said guiding means for moving out of alinement with the needle of the stitching mechanism such fasteners as come into alinement therewith, means extending downwardly to a point below the plane of the said guiding means for supporting said third named

means, and means for operating the said supporting means.

In testimony that I claim the foregoing as my invention, I have hereunto signed my name this 11th day of November, A. D., 1926.

ABRAHAM BEBEL.
